Primary Examiner — Cynthia R Underwood*(74) Attorney, Agent, or Firm* — Oliff PLC(57) **CLAIM**

The ornamental design for a climbing apparatus, as shown and described.

DESCRIPTION

FIG. 1 is a rear, left-side, bottom perspective view of the climbing apparatus;

FIG. 2 is a left-side elevational view thereof;

FIG. 3 is a right-side elevational view thereof;

FIG. 4 is a front elevational view thereof;

FIG. 5 is a rear elevational view thereof;

FIG. 6 is a top plan view thereof;

FIG. 7 is a bottom plan view thereof; and,

FIG. 8 is a rear, right-side, bottom perspective view thereof. The broken lines depict parts of the climbing apparatus that form no part of the claimed design.
